BRAIDING MACHINE

Alfred Gamba, Wildegg, Switzerland

Application April 4, 1934, Serial No. 718,987
In Switzerland December 9, 1932

2 Claims. (Cl. 96—12)

The present invention relates to improvements in braiding machines and particularly to an arrangement of the driving gear of the shuttle carriers in braiding machines in which these driving 5 gears are arranged around a central gear in two groups on two concentric circles of different diameters where the wheels of the smaller circle are meshing with the central wheel and are inserted alternately between and meshing with the wheels 10 of the larger circle. In this arrangement the raceways of the wheels of the smaller circle are connected to the raceways of the wheels of the larger circle and to the raceway of the center wheel by means of interchangeable rotatable 15 switch plates either of the two way type or a mixed type having a central way and two adjacent curved ways.

The annexed drawing represents a working example of an arrangement according to the present invention:

In Fig. 1 by a plan showing on the left hand side the driving gears and on the right hand side the raceways and switch plates.

Fig. 2 is a vertical section on line II—II in Fig. 1. 25 In the drawing a group of driving gears 1 is concentrically arranged around a central gear 2. The gears 1 are alternately arranged on a smaller and on a larger circle. The driving gears 3¹ of the smaller circle mesh with the central wheel 3 and the gears 3² of the larger circle mesh only with the gears 3¹. All these gears are provided 30 with notches 11 for the transporting and transferring of the shuttle carriers, not shown, from one raceway to an adjacent raceway. The distances between the notches are also chosen so that the notches of the different wheels will always 35 meet each other.

The raceways 7, 7¹, 7² are cut into segmental raceway-plates 4 screwed fast to a base plate 5 by 40 means of screws 4¹. The supporting posts 6 of the driving gears are screwed fast to the bed plate 5. As means for transferring the shuttle carriers from one raceway to the other there are interchangeable and rotatable switch plates 9¹, 9² fitted 45 into the raceway plate 4 and are forming the connections between the raceways. The switch plates 9¹ are of the two way type having two ways crossing each other and the switch plates 9² are of a compound type having a central straight way 50 and two adjacent curved ways. The gear wheel 10 arranged on the larger circle serves as driver for all other wheels. The raceway of this wheel 10 is connected by a switch plate 8² of the compound type with the raceway of the next wheel 7² 55 disposed on the larger circle.

In the Fig. 1 there are shown in all ten drive wheels arranged on two concentric circles of different diameters around a central wheel. When counting from right to left the raceways of the third and fourth wheels and of the fifth and sixth 60 wheels are connected with the raceways of the adjoining wheels by compound switches in such a position that said two pairs are cut off and working each together independently from the rest. In a similar way the raceways of the seventh and 65 ninth wheels are working together because the compound switches which connect the raceways of the adjoining wheels, that is of the center, the sixth, the eighth and the tenth wheel, are in such a position that the raceways of these wheels are 70 thrown out of cooperation.

According to the Fig. 2 cam plates 12 are rigidly connected with the drivers 1 and are adapted to adjust automatically the switch plates 9² by means of pins 13 provided on said switch plates. 75

What I claim is:

1. In a braiding machine the combination of driving gears having a notched circumference for the spool carriers and each cooperating with a circular raceway said combination comprising a 80 central driving gear, and two groups of mutually intermeshing drivers arranged around said central wheel on two concentric circles of different diameter, only the wheels of the smaller circle meshing also with the central wheel, and interchangeable rotatable switch plates of a cross type and a compound type inserted between the raceways of intermeshing gears and adapted to include or exclude the adjoining raceway according to the adjusting of said switches. 85

2. In a braiding machine according to claim 1 and in combination cam plates rigidly connected to the driving gears and pins attached to the switch plates both adapted to effect the automatic adjusting of the switch plates by the driving gears. 95

ALFRED GAMBA.
